UNITED STATES PATENT OFFICE.

JOHN C. KUPFERLE AND PETER WHITE, OF ST. LOUIS, MISSOURI.

IMPROVEMENT IN HYDRANT-VALVES.

Specification forming part of Letters Patent No. 174,824, dated March 14, 1876; application filed January 26, 1876.

To all whom it may concern:

Be it known that we, JOHN C. KUPFERLE and PETER WHITE, both of St. Louis, Missouri, have invented an Improved Hydrant, of which the following is a specification:

This invention relates especially to hydrant-valves for discharging liquids or fluids, although the constructive principle is also applicable for closet-valves and valve-cocks in general.

This invention relates to an improved construction of parts; also to their combination to operate in the manner as will now more fully appear.

Of the drawing, Figure 1 is a sectional elevation, showing the operative parts when the hydrant is running and waste is closed. Fig. 2 is an enlarged detailed section of the operating parts when the hydrant is closed and waste is running. Figs. 3 and 4 are respective details of detail parts, Fig. 5 being a detail view of the forked lever and pin.

A, Fig. 1, is a suitable housing. B, Figs. 1 and 2, is the shell or body of the cock, and which we adapt for the operating parts as follows: At b^1 is a valve-seat. At b^1 we provide annular screw-threads to secure the cage. At b^2 is a shoulder or seat for the elastic ball or washer. The top part of the shell at b^3 is forced off, making a seat for a funnel-shaped casting. Also, forming part of B, is the inlet-branch B^1 , and discharge-branch B^2 , to which, respectively, the water-inlet pipe, as well as discharge-pipe or nozzle, are connected, and as shown in Fig. 1. The shell B thus cast or made by its side flanges is properly secured within the housing A. c is the valve proper. This forms part of a valve-stem, c^1 . (See Figs. 1 and 2.) Immediately above the valve its stem is triangular-shaped to create inlet-spaces for the water to rise. The valve c operates on the under side of its seat, and so that when lowered the water finds entrance to be discharged from the hydrant, and when said valve rises from the pressure it closes against its seat. A washer, c^2 , (see Figs. 1, 2,) is passed over the valve-stem c^1 to seat top of valve-seat, and form a water-tight joint for the cage.

D is a cage, being a cylinder casting open at top and bottom, having outside upper screw-

threads at d , loosely-fitting inner lugs at d^1 , port-holes at d^2 , as shown in Figs. 1 and 2. The threads on the cage are to secure same stationary to the threads of the shell at b^1 , while the lugs d^1 are to engage corresponding grooves in a center valve stem to permit same and its lower connected parts to be raised and lowered; also, to enable the cage to be screwed or unscrewed from the shell by the turning of said center stem.

The cage D is passed on the valve-stem c^1 , and this is next connected to the center valve-stem E, the top threads of the valve-stem for this purpose being screwed into the socket end of said stem E, and as shown in Figs. 1 and 2. It is, therefore, an easy matter to replace the lower washer or valve or stem, when said parts need repairs.

Further, we provide the center stem E with an elastic ball, E' , securely seated between an upper flange at e and the lower shoulder at e^1 . (See Figs. 1 and 2.) The ball E' (which can be also a washer or its equivalent) is chiefly for the purpose of stopping off waste when the valve is open, it being operated to this end to close on its seat at b , and when raised to permit the waste to escape. It can, therefore, be here stated that the play of the cage around the center stem E, as well as the play of the lugs d in said stem, is sufficient to permit the waste water to enter the waste port of the shell and to be discharged from same through waste-holes e^2 .

To the center stem E is further connected the rod F; hence this has its lower square-shaped end engaging the socket at top of the said stem E, the joint being completed by a coupling-pin, f . (See Fig. 1.) This connection permits us to use cheap or ordinary rods, the lower parts being of brass.

G is a funnel-shaped casting, (see Figs. 1 and 2,) which rests on the top shoulder b^3 of the shell B. (See Fig. 1.) It can either be the casting, as shown, or a pipe or tubing with an interior funnel shape, and having screw-threads at bottom to engage screw-threads which can be provided on the inner face of b^3 .

The purpose of this funnel casting is to guide the insertion properly of the rod F carrying the lower operating parts described, in

order to seat same in operative position in the shell of the cock. Said casting has its sides properly secured to the sides of the housing.

H, Figs. 1 and 4, is a fulcrum-plate for the hand-lever I. The part H consists of a face-plate, *h*, forming part of which are projecting lugs *h'*. (See Fig. 1.) The top of the lugs and plate is left open to receive the hand-lever.

We secure the part H by its face to the side of the housing, having its lugs projecting inside. (See Fig. 1.)

The hand-lever I has its fulcrum at *i*, its inner end in form forked (see Fig. 5) so as to be capable of easy connection and disconnection from the rod F, and also so that same can be, beside its reciprocation, turned, in order to screw or unscrew its lower parts, and follow up wear of parts. Hence, the forked end of the lever engages a sleeve, *i'*, which is secured to the rod, and so that the lever-bearings at *i''* shall engage the top and lower flanges at *i'''* of said sleeve. (See Fig. 1.) A coupling-pin, *i⁴*, secures the connection.

J, Figs. 1 and 3, is a circular plate or casting. This has holes *j* surrounding its entire circumference, in line with the top of the housing, to which it is secured. Further, J has in its center a square hole, *j'*, to engage the corresponding top of the rod F, the object of the hole *j* being to enable us to secure the plate at any point to the top of the housing, and according to the required position determined by that of the rod F and its lower parts. Further, this connection of the plate J to rod F serves to steady and guide same in its operation, and otherwise it can be used in place of a wrench to turn the said rod, screw or unscrew its cage, and cause the valve-gear to follow up wear that takes place and to prevent leakage of the parts. K is the top cover or cap. This simply covers the top of the housing, also the open socket-top of the fulcrum-plate H, and as shown in Fig. 1.

The parts being thus constructed and arranged the operation of our hydrant will be as follows: By raising the lever it presses down the rod F and opens the valve *c*, allowing the liquid to pass out of the discharge-pipe. At the same time the elastic ball *E'* is pressed against the flat or taper seat in the top of the shell *b*, thus making the top joint on waste-hole perfectly tight while the pressure is passing through. When the lever is released, its weight, together with the pressure of the fluid, raises the valve *c* up against the seat, which immediately shuts off the main pressure. At same time the elastic ball is raised, thereby allowing the fluid that remains in the pipe to pass out of the waste-hole, preventing freezing, &c. In case of repairs the cap is removed from the box, the hand-lever is disconnected from its fulcrum-pin, also drawn out from the sleeve *i'*, which leaves the rod F free and easily to be unscrewed by a wrench, which forces the cage to unscrew, and thus the whole valve can be

removed from the box. When repaired the parts are replaced by screwing the cage tight to its place, (the funnel guiding this operation.) This done, replace lever and cover, and the hydrant is ready for reuse.

What we claim is—

1. The cage D, having inner lugs at *d¹*, in combination with corresponding grooves in the lower end of a center valve-stem, as and for the purpose set forth.

2. The cage D, having screw-threads at *d*, in combination with the threaded shoulder *b¹* of the shell B, as and for the purpose set forth.

3. The center valve stem E, having shoulders *e e¹*, and carrying an elastic ball, *E'*, as and for the purpose set forth.

4. The lower valve-stem *c¹*, carrying valve *c*, washer *c²*, cage D, in combination with a center valve-stem, E, as set forth.

5. The washer *c²*, in combination with the cage D and valve-seat *b*, as and for the purpose set forth.

6. The lower valve-stem *c¹*, its valve *c*, washer *c²*, cage D, center valve-stem E, and shell B, said parts being constructed to operate as and for the purpose set forth.

7. The shell B, having screw-threads at *b¹*, shoulder *b²* and *b³*, as and for the purpose set forth.

8. The center valve-stem E, carrying a ball, *E'*, the lower valve-stem *c¹*, carrying valve *c*, the washer *c²*, the cage D, having threads at *d*, inner lugs at *d¹*, in combination with the shell B, having valve-seat *b*, screw-threads at *b¹*, shoulder at *b²*, substantially as and for the purpose set forth.

9. The rod F, secured by pin *f* to a center valve-stem, E, carrying ball *E'*, the lower stem *c¹* carrying valve *c*, the washer *c²*, in combination with a cage, D, to operate as and for the purpose set forth.

10. The fulcrum-plate H, consisting of a face-plate, *h*, having inner projecting lugs, as and for the purpose set forth.

11. The connection of the forked lever I by a coupling-pin, *i⁴*, in combination with the sleeve *i'*, having shoulders *i''*, to operate in the manner shown and described, and for the purpose set forth.

12. The circular plate J, having holes *j* and square center *j'*, as and for the purpose set forth.

13. The combination of the circular plate J, with the rod F, to operate as and for the purpose set forth.

14. The combination of the cap K with a fulcrum-plate, H, consisting of a face-plate, *h*, in order to close the top of said face-plate, as set forth.

In testimony of said invention we have hereunto set our hands in presence of witnesses.

JOHN C. KUPFERLE.
